COMBINED CONTAINER AND CLEANER FOR ARTIFICIAL EYELASHES

Howard Aylott, Welwyn Garden City, England, assignor to Eylure Limited, Garden City, England, a company of Great Britain

Filed July 12, 1965, Ser. No. 86,106

Claims priority, application Great Britain Feb. 12, 1965

Term of patent 14 years

(Cl. D86—10)

FIG. 2.

FIG. 3.

FIG. 4.

FIG. 5.

FIG. 6.

Fig. 7.

FIG. 1 is a top plan view of a combined container and cleaner for artificial eyelashes showing my new design in fully open condition;

FIG. 2 is a sectional view thereof taken on line II—II of FIG. 1;

FIG. 3 is a sectional view taken on line III—III of FIG. 1;

FIG. 4 is a side elevational view thereof in the direction of line IV, the side opposite being identical thereto;

FIG. 5 is a top plan view of the removable holder seen in FIGS. 1, 2, 3, 4, and 7;

FIG. 6 is a sectional view thereof taken on line VI—VI of FIG. 5; and

FIG. 7 is a perspective view of the combined container and cleaner for artificial eyelashes in a partially open condition.

The top, bottom and sides of the container are of flat, planar configuration.

I claim:

The ornamental design for a combined container and cleaner for artificial eyelashes, as shown and described.
